EDWARD F. KUNATH, OF JERSEY CITY, NEW JERSEY, ASSIGNOR TO
UNDERWOOD TYPEWRITER COMPANY, OF NEW YORK, N. Y., A
CORPORATION OF NEW JERSEY.

TYPE-WRITING MACHINE.

No. 820,505.

Specification of Letters Patent.

Patented May 15, 1906.

Application filed May 29, 1905. Serial No. 282,832.

To all whom it may concern:

Be it known that I, EDWARD F. KUNATH, a citizen of the United States, residing in Jersey City, in the county of Hudson and State of New Jersey, have invented certain new and useful Improvements in Type-Writing Machines, of which the following is a specification.

This invention relates to tabulating devices for type-writing and other machines.

In using tabulating mechanism for different kinds of work it is customary to readjust the column-stops along the column-stop bar each time that a different class of work is to be done, so as to meet the different requirements; the columns of one class differing in width and location from another.

The principal object of my invention is to provide improved means for bringing different sets of column-stops into effective position, so that when it is desired to change from one kind of work to another it will be necessary only to move a finger-piece, whereby the appropriate column-stops will be set for the new kind of work. To this end I provide in the preferred form of my invention a single row or series of column-stops placed side by side and, if desired, abutting one against another and each movable independently of the others into and out of working position. I also provide a bar or barrel extending along the series of column-stops and having different sets of projections upon its periphery. This bar may be rotated by a finger-piece, so as to cause any set of its projections to act upon the corresponding column-stops and move some of the latter to idle position. Said revoluble bar may have any desired number of sets of projections thereon, and by rotation of the bar any one of said sets may be brought into use. The sets of projections extend along the bar, and all of the projections in each set are brought into use simultaneously.

In the accompanying drawings, in which my invention is shown as applied to the well-known "Underwood" type-writing machine, Figure 1 is a rear view and Fig. 2 a top view of the usual Underwood tabulator mechanism provided with my improvements. Fig. 3 is a perspective view thereof. Fig. 4 is a sectional view showing the tabulator and a

portion of the carriage and carriage-feeding devices.

Upon the usual carriage 1 is mounted a 55 rack 2, meshing with a pinion 3, connected to an escapement-wheel 4. Coöperating with the latter are the usual dogs 5, operated by the finger-keys. (Not shown.) Upon the carriage, which as usual is power-driven, is 60 fixed the usual stop 6, which coöperates with the several column-stops to arrest the released carriage in the proper position to begin writing in the desired column. In place of this stop may be substituted any suitable 65 set of denomination-stops, and it will also be understood that within the scope of my invention it is feasible to place the single stop or the denomination-stops upon the machine-frame and to mount the column-stops with 70 their appurtenances upon the carriage.

The column-stops are designated as 7 and are pivoted side by side upon a cylindrical rod 8, so that any stop may turn independently of the other stops. Said rod 8 is fixed 75 at its ends in a pair of rock-arms 9 10, whose upper ends are joined by a rack-bar 11, and the lower ends by a square rock-shaft 12, said bar and rock-shaft forming a rigid frame which is hinged at 13 upon the framework 14 80 of the machine. Each of said stops has teeth 15 to engage the teeth of the rack 11, thereby preventing displacement of the column-stops along the rod. It will be seen that the principal portion of the space between the arms 9 85 10 is occupied by the column-stops, some thirty being shown within the space of about nine inches and these being sufficiently numerous for practical purposes, although more can be assembled within the same space, if 90 required, by making each one thinner. A spring 16 tends normally to hold the teeth 15 upon each stop in engagement with the rack 11, said spring being mounted within a recess in the stop and pressing down a ball or round 95 plunger 16^a, the latter engaging a groove 17, which extends longitudinally of the rod 8. The rod is also provided with a longitudinal groove 18 back of the groove 17, so that any stop may be swung way back by means of a 100 handle 19 and there held by the engagement of the spring-ball with the groove 18.

Along the single row of stops extends a bar 20, which is revolvably mounted in bearings

20^a and 20^b, fixed upon the rock-arms 9 10. Said bar has four sets of projections, each extending longitudinally of the bar, and the sets being numbered respectively 21, 22, 23, and 5 24. The projections in each set are adapted to strike down upon the handles or projections 19 of the stops and vibrate the latter rearwardly upon the rod 8 into idle position. Only those stops which are not operated by 10 said projections upon the bar 20 are left in effective position, as at A, the idle position being shown at B, and the position when the stops are normally moved out of engagement with the rack 11 being seen at C. In each set 15 the stops upon the bar 20 are disposed differently from those in the other sets, so that when any set is brought into use a different arrangement of column-stops is effected. The bar, and the projections thereon may be 20 otherwise formed, and either less or more than four sets of stops may be used.

Upon the end of the bar 20 is fixed a finger-piece or wheel 25, which is provided with numbers, as seen at Figs. 1 and 2, to indicate 25 to the operator which set of projections, and hence which set of column-stops, is in use. If desired, an index 26 may be fixed upon the machine to point to the numbers upon the wheel 25.

30 In use the revoluble bar 20 is turned to the left at Fig. 4 to bear down the handles 19 of the stops that are not wanted, while all other stops are moved or held up in working position by their springs 16. The bar always 35 turns in the same direction in shifting from one set of sets to another. The parts are so proportioned that the handles 19 escape the lower stops when they are just past the position occupied by 24 at Fig. 4, thus permitting 40 the springs 16 to lift the stops to effective position. It will be seen that the lower projections 24 are in use, since they hold down the handles 19 upon some of the stops, while by a slight turn to the left the depressed handles 45 19 are released and move up, while the same or other handles are carried down by the succeeding set of stops 21. The operator needs only to revolve the finger-wheel 25 until the desired number thereon is brought into view 50 or comes opposite the index 26.

Upon the left-hand end of the bar at Fig. 2 is formed a square shoulder 27, which is received by a recess 28, formed in the bearing member 20^a, whereby revolution of the bar 20 is prevented, and the projections, as 24, are enabled to hold down the handles 19 against the tension of the springs 16. In order to release the bar, it is moved sidewise to the right at Fig. 3 by pressing upon the finger-piece 25; whereby the shoulder is withdrawn from the recess 28. The bar is then rotated and when the desired number comes 55 opposite the index 26 the bar is released and a compression-spring 29, secured to the bar, 60 presses the same to the left until the shoulder

27 again enters the recesses, thereby holding the bar fixed with the set of projections 21 holding down the corresponding handles 19. Thus any of the four or more sets of projections may be brought into use merely by 70 turning the finger-piece 25, without the necessity of readjusting the column-stops along the rod as heretofore.

It will be understood that the teeth 15 upon the stops are sufficiently long to remain in engagement with the rack 11 during the rotation of the bar 20; but when desired any of the stops may be swung back until said teeth are disengaged from the rack, when the spring-ball 16^a enters the groove 18. Thus 80 one or more of the stops may be swung out of use and out of control of the bar 20, and some of the end stops may be moved out of the range of said bar, as at C, or in some cases may be adjusted along the bar, if desired. 85

The type-keys are manipulated in the usual manner and the tabulating-key 30 is depressed and acts upon a link 31, connected to an arm 30^a upon the rock-shaft 12, thereby rocking the column-stop frame forwardly until the active column-stops in position A are brought into the path of the stop 6 upon the carriage. Upon the shaft 12 is fixed an arm 32, which acts upon a lever 33 to lift the carriage-rack 2 out of engagement with the pinion 3, so that the carriage may be drawn along rapidly by its spring. 90

Variations may be resorted to within the scope of my invention, and portions of my improvements may be used without others. 100

Having thus described my invention, I claim—

1. The combination with a carriage and a letter-feeding mechanism, of a stop, a single row of column-stops to coöperate with said stop, a revoluble selector-bar extending along said row, and means for enabling a rotative movement of said bar to select and move different sets of stops. 105

2. The combination with a carriage and a letter-feeding mechanism, of a stop, a row of column-stops to coöperate with said stops, a selector-bar extending along said row, and having wholly independent and distinct rows of stop-controllers thereon, and means for enabling said controllers to select and effect the movement of different sets of stops into idle position. 115

3. The combination with a carriage and a letter-feeding mechanism, of a stop, a row of column-stops to coöperate with said stop, and a revoluble selector-bar extending along said row and provided with wholly independent and distinct sets of controllers for selecting and moving different sets of stops. 120

4. The combination with a carriage and a letter-feeding mechanism, of a stop, a row of column-stops to coöperate with said stop, means tending constantly to hold said stops in effective position, a selector-bar extending 125

along said row and provided with wholly independent and distinct rows of controllers for selecting and moving different sets of stops into idle position and holding them there, and means for detaining said bar in different predetermined positions.

5. The combination with a carriage and a letter-feeding mechanism, of a stop, a single row of column-stops to coöperate with said stop, a revolute selector-bar or drum extending along said row, projections upon said bar, and means upon said stops engageable by said projections for controlling the positions of different predetermined sets of said 15 stops.

6. The combination with a carriage and a letter-feeding mechanism, of a stop, a row of independently-movable column-stops to coöperate with said stop, a movable selector-bar having thereon a plurality of rows of projections, one row behind another, and means upon said column-stops engageable by said projections for controlling the positions of different predetermined sets of the column- 25 stops.

7. The combination with a carriage and a letter-feeding mechanism, of a stop, a single row of column-stops to coöperate with said stop, said column-stops being movable independently of one another into effective position, a revolute selector-bar, means for detaining said bar in a plurality of rotative positions, and means controlled by the bar for selecting and moving different sets of stops 30 at different points in the revolution of the bar.

8. The combination with a carriage and a letter-feeding mechanism, of a stop, a single row of column-stops to coöperate with said stop, a selector-bar extending along said row, and separate and distinct rows of controllers, each row complete in itself, and one row behind another, for enabling said bar to move either of a plurality of previously-selected 40 sets of stops, and means for holding the stops in and out of effective position.

9. The combination with a carriage and a letter-feeding mechanism, of a stop, a row of pivoted column-stops to coöperate with said stop, springs tending constantly to move said stops to effective position, a bar having separate and distinct rows of projections to engage and move said stops into idle position, each row complete in itself, and one row 50 behind another, and releasable means for 55

holding said bar in a plurality of predetermined positions.

10. The combination with a carriage and a letter-feeding mechanism, of a stop, a rod, column-stops pivoted side by side upon said rod, a spring for turning each column-stop upon the rod, a rotative bar having means to select and turn different sets of column-stops, a finger-piece connected to said bar, and means for detaining said bar in a plural- 60 65 ity of rotative positions.

11. The combination with a carriage and a letter-feeding mechanism, of a stop, a single row of column-stops having projections, and a bar having different and distinct rows of 70 projections, one row behind another, for engaging the projections upon said column-stops, and moving different sets thereof, each row of projections complete in itself and independent of the remaining rows. 75

12. The combination with a carriage and a letter-feeding mechanism, of a stop, a row of column-stops, a revolute bar having sets of projections to engage different sets of stops and move them from normal position, a detent for preventing rotation of said bar, the latter being movable endwise to become released from said detent, and a spring to move the bar endwise and render said detent effective. 80

13. The combination with a carriage and a letter-feeding mechanism, of a stop, a row of column-stops, a bar having sets of projections to engage different sets of stops and move them from normal position, bearings 90 in which said bar is mounted for both rotation and endwise movement, an angular shoulder upon said bar, a recess in one of said bearings to receive said shoulder and prevent the bar from rotating, and a spring to hold 95 said shoulder within said recess.

14. The combination with a carriage and a letter-feeding mechanism, of a stop, a row of pivoted column-stops to coöperate with said stop, springs tending constantly to hold said 100 stops in effective position, a revolute bar having sets of projections to engage and move said stops into idle position, a finger-piece upon said bar, and means releasable by said finger-piece for holding said bar in a plurality 105 of relative positions.
